ATTORNEYS

UNITED STATES PATENT OFFICE.

HAROLD F. BELK, OF EAST ST. LOUIS, ILLINOIS.

SWING.

Application filed July 3, 1922. Serial No. 572,492.

To all whom it may concern:

Be it known that I, HAROLD F. BELK, a citizen of the United States, residing at East St. Louis, Illinois, have invented a certain new and useful Improvement in Swings, of which the following is a full, clear, and exact description, such as will enable others skilled in the art to which it appertains to make and use the same.

10 This invention relates to swings, and has for its main object to provide a swing of the type commonly referred to as a "rope swing" that can be operated easily by the user or users and without the necessity of 15 requiring some one to push the swing.

Another object is to provide a safe, inexpensive swing that is compact and easy to install.

Briefly stated, my invention consists of 20 a swing composed of a seat, a flexible sustaining means for said seat suspended from an overhead supporting structure, a foot rest supported at one end by a flexible sustaining means and means for suspending the 25 opposite end of said foot rest from said seat in such a manner that the seat will be caused to swing forwardly when the occupant of same exerts a forward thrust on the 30 foot piece. The swing can be constructed either in the form of a single swing provided with one seat, or constructed in the 35 form of a double swing provided with two seats arranged in such a manner that the occupants of same face each other, as in the conventional "lawn" swing.

Figure 1 of the drawings is a perspective view of a double swing constructed in accordance with my invention; and

Figure 2 is a perspective view of a single swing constructed in accordance with my invention.

Referring to Figure 1 of the drawings which illustrates one form of my invention, A and A' designate two seats arranged in such a manner that the occupants of same face each other, B designates a flexible sustaining means for the seat A composed preferably of two strands of rope, cable or other flexible material connected at their upper ends to an overhead supporting structure and B' designates a flexible sustaining means for the seat A' consisting of two strands of rope, cable or the like connected at their upper ends to the same overhead supporting structure. Each of said sustain-

ing means may consist of a single strand of rope or the like, doubled intermediate its ends and passed through holes in the seat, or it may consist of two separate short strands connected at their upper ends to the 60 supporting structure and at their lower ends to the seat.

The swing comprises a movable foot rest C connected at its opposite ends by swinging links 1 and 1^a to the seats A and A', respectively, and provided with cross pieces 2 and 2^a on which the feet of the occupants of the swing rest. The particular construction of said foot rest is immaterial, so far as my invention is concerned, but it can be 65 formed conveniently from two parallel pieces of angle iron 3 arranged with their horizontal legs projecting inwardly towards each other and rigidly connected together by the cross pieces 2 and 2^a. The swinging 70 links 1 and 1^a that sustain the foot rest C are pivotally connected at their upper ends to brackets 4 on the undersides of the seats A and A' and the lower ends of said links are pivotally connected to the foot rest C 75 preferably by upset rods or long rivets 5 that extend transversely through said links and foot rest and through tubular spacing members 6 interposed between the angle iron 80 pieces 3 of the foot rest.

The swing may be operated either by the occupant of the seat A pushing forwardly on the cross piece 2 so as to exert a forward pull on said seat and on the sustaining members B, thereby imparting a forward stroke to the seat A and a rearward stroke to the seat A', and the occupant of the seat A' thereafter pushing forwardly on the cross piece 2^a so as to impart a forward stroke to the seat A' and a rearward stroke to the 95 seat A, or the occupants can grasp the ropes or flexible sustaining members B and B' with their hands and pull rearwardly on same while pushing forwardly on the cross pieces of the foot rest C so as to "pump" 100 the swing in substantially the same manner that the conventional rope swing is operated.

Preferably, the flexible members B that sustain the seat A are connected to the flexible members B' that sustain the seat A' 105 by two strands of rope D or the like so as to cause said flexible seat sustaining members to oscillate in unison and also transmit motion from the sustaining members B to the sustaining members B' and vice versa, when 110

the swing is in operation. If desired, each of the seats may be provided with a back, the swing illustrated in Figure 1 being equipped with a back E for the seat A and 5 a back E' for the seat A' composed of a piece of fabric connected at its lower end to the rear edge of the seat, as shown in Figure 1, and provided at its sides with casings 7 through which the flexible seat sustaining 10 members pass, but it is immaterial whether or not the seats are provided with backs.

In Figure 2 of the drawings I have illustrated my invention embodied in a single swing composed of one seat A, flexible 15 sustaining members B for said seat, a foot rest C equipped with a cross piece 2 and connected at one end to the seat A by means of swinging links 1 and a flexible member F consisting of a piece of rope or 20 other suitable material for sustaining the opposite end of the foot piece C, the member F being connected at its upper end to the overhead supporting structure to which the seat sustaining members B are connected 25 and having its lower end connected to a cross bar 8 fastened to the side pieces 3 of the foot rest C. If desired, flexible members D' of rope or the like can be connected to the seat sustaining members B and to 30 the flexible foot rest sustaining member F, so as to cause the members F and B to oscillate in unison and also to transmit movement from the members B to the member F and vice versa. The swing illustrated in 35 Figure 2 can be operated in the same manner as the swing illustrated in Figure 1, namely, by pushing forwardly on the cross piece 2 of the foot rest and pulling rearwardly on the seat sustaining members B 40 so as to cause the seat to swing forwardly and rearwardly.

A swing of the construction above described embodies all of the desirable characteristics and features of a "lawn" swing, 45 but it is not as cumbersome and expensive as a "lawn" swing, as the seat or seats are sustained by flexible members connected to an overhead supporting structure, and the foot rest consists of a light-weight frame of 50 skeleton construction that is suspended from the seats of means of swinging links. Moreover, such a swing embodies the desirable characteristics of the conventional rope swing, in that the means which sustains the seats consists of strands of rope or 55 the like on which the occupants pull rearwardly to set the swing in operation and keep it in motion, but it is a decided improvement on the conventional "rope swing", in that it is of such design that it 60 is not necessary to have some one push the swing to keep it in operation. Such a swing can be stored in a small space when it is not in use; it can be easily attached 65 to the ceiling of a room or a porch and it

is of such simple construction that it can be manufactured and sold at a low cost.

Having thus described my invention, what I claim as new and desire to secure by Letters Patent is:

1. A swing, comprising a seat, flexible sustaining members for said seat connected to an overhead supporting structure, a foot rest suspended at one end from said seat by swinging links, a flexible sustaining 75 means for the opposite end of said foot rest connected to said supporting structure, and ropes or the like that join said flexible foot rest sustaining means to said flexible seat sustaining members.

2. A swing, comprising a pair of seats arranged so that the occupants face each other, pairs of flexible members for sustaining said seat, a foot rest, a pair of 80 swinging links suspended from each of said seats and pivotally connected to one end of said foot rest, and flexible devices that connect said pairs of sustaining members together.

3. A swing, comprising a pair of seats arranged so that the occupants of same face each other, pairs of flexible sustaining members of said seats connected to an overhead supporting structure, a foot rest composed of longitudinal members and cross 90 pieces that connect said members together, a pair of swinging links depending from each of said seats, tubular spacing devices 95 interposed between the parallel members of the foot rest, and rivets extending through said spacing devices that join said links to the parallel members of the foot rest.

4. A swing, comprising a pair of seats arranged so that the occupants of same face each other, pairs of flexible sustaining members for said seats connected to an overhead supporting structure, a foot rest composed of longitudinal members and cross pieces that connect said members together, 100 a pair of swinging links depending from each of said seats, tubular spacing devices interposed between the parallel members of the foot rest, rivets extending through said spacing devices that join said links to the parallel members of the foot rest, backs for said seats combined with said seat sustaining members, and flexible devices that connect together the flexible sustaining 110 members of the respective seats.

5. A swing, comprising a pair of seats arranged so that the occupants face each other, flexible sustaining members for said seats, a rigid foot rest suspended from said seats by swinging links, and flexible devices that join the sustaining members of the respective seats together, for the purpose described.
